(57) **CLAIM**

The ornamental design for an expandable trolley traveling bag, as shown and described.

DESCRIPTION

FIG. 1 is a perspective view of an expandable trolley traveling bag;

FIG. 2 is a front view thereof;

FIG. 3 is a back view thereof;

FIG. 4 is a left side view thereof;

FIG. 5 is a right side view thereof;

FIG. 6 is a top view thereof;

FIG. 7 is a bottom view thereof;

FIG. 8 is a perspective view of the embodiment shown in FIG. 1 wherein all expanded portions are enclosed.

FIG. 9 is a front view of FIG. 8.

FIG. 10 is a back view of FIG. 8.

FIG. 11 is a left side view of FIG. 8.

FIG. 12 is a right side view of FIG. 8.

FIG. 13 is a top view of FIG. 8; and,

FIG. 14 is a bottom view of FIG. 8.

The pattern is partially shown for convenience of illustration. It is understood that the pattern is uniformly continuous over the surface of the expandable trolley traveling bag.
